UNITED STATES PATENT OFFICE.

SIMON CLARY, OF CARNEGIE, PENNSYLVANIA.

RAIL-PLATE.

No. 836,436.

Specification of Letters Patent.

Patented Nov. 20, 1906.

Application filed April 6, 1906. Serial No. 310,380.

To all whom it may concern:

Be it known that I, SIMON CLARY, a citizen of the United States of America, residing at Carnegie, in the county of Allegheny and State of Pennsylvania, have invented certain new and useful Improvements in Rail-Plates, of which the following is a specification, reference being had therein to the accompanying drawings.

10 This invention relates to certain new and useful improvements in rail-plates; and the invention relates more particularly to a series of plates adapted to be supported by ties or sleepers to form a base or foundation for a main rail and a guard-rail.

15 The primary object of the invention is to provide a novel form of rail-plate particularly adapted to support a main rail and one of my improved guard-rails, such as is shown 20 in patent granted to me August 22, 1905, No. 797,939. The guard-rail disclosed in this application is designed to either overlap or underlap the main rail, thereby preventing the guard-rail from being displaced relatively to 25 the main rail and preventing the same from tilting or tipping.

20 In constructing my improved rail-plate I aim to provide a seat for my improved guard-rail and also provide means of adjustment, 30 whereby the peculiarly-formed base-flange of the guard-rail will lie beneath the plane of the base of the main rail, at the same time rest upon the rail-plate and prevent the guard-rail from becoming laterally displaced.

35 With the above and other objects in view, which will more readily appear as the nature of the invention is better understood, the same consists in the novel construction, combination, and arrangement of parts to be 40 hereinafter more fully described and claimed, and, referring to the drawings accompanying this application, like numerals of reference designate corresponding parts throughout the several views, in which—

45 Figure 1 is a plan of a section of rail having a guard-rail, said rails being supported by my improved rail-plates. Fig. 2 is a plan of a series of plates constructed in accordance with my invention. Fig. 3 is a cross-sectional view taken on the line $x-x$ of Fig. 1.

50 In the accompanying drawings I have illustrated a section of rail 1, commonly known as a "main" rail. Associated with the main rail 1 is a guard-rail 2, said rail having

its ends bent outwardly, as at 33. The inner 55 base-flange 4 of the guard-rail 2 is bent downwardly to form a seat 5 for the inner base-flange 6 of the main rail 1, and in order that my improved guard-rail, the detail construction of which is disclosed in another 60 patent, may be supported by ties 7 I have devised a series of rail-plates.

In connection with the present type of main rail my improved series of plates consists of nine plates, one plate to a tie or 65 sleeper. The three central plates 8 of the series are of equal length, while the length of the remainder of the plates varies. As the central portion of the guard-rail 2 lies in closer proximity to the main rail 1 than the 70 outwardly-bent ends 33, the central plates 8 need not necessarily be as long as the three end plates 9 at each end of the series, said end plates gradually increasing in length until the outwardly-bent ends 3 of the guard-rail 2 have been firmly supported by said 75 plates.

As the three central plates 8 are identical in construction, I deem it only necessary to describe one of said plates, reference being had 80 particularly to Fig. 3 of the drawings, where one of the plates 8 is illustrated in cross-section. The outermost edge of each plate 8 is provided with a transverse ridge or raised portion 10 and with two vertically-disposed 85 openings 11 and 12, said openings being disposed one closer to the end of the plate than the other, whereby the outer base-flange of the main rail 1 can be adjusted upon the plate 8 and secured to said plates by spikes 90 14, which enter the ties 7, supporting the central plates 8. The opposite end or edge of each plate 8 is also provided with a ridge 15, similar to the ridge 10; but the vertically-disposed openings 16 16, formed in this end or 95 edge of the plate, are in a line parallel to the axis of the rail.

Intermediate the ends or edges of each plate 8 is formed a transverse seat or groove 17 to accommodate the base-flange 4 of the 100 guard-rail 2, thereby permitting the rails 1 and 2 to be supported upon a horizontal plane relative to one another, such as the plates 8. The seat or groove 17 of the plates 8 is provided with a vertically-disposed slot or oblong opening 18, while the base-flange 4 of the guard-rail 2 is provided with similar openings 19. The openings 18 and 19 per-

mit of the spikes 20 being driven into the ties 7 to engage the inner flange 6 of the main rail 1 and firmly hold said main rail upon its rail-plates. The oblong openings 18 and 19 also 5 permit of the main rail having a greater width of base than the rail shown, being mounted upon the plate 8 and secured thereto.

Reference now being had to the end plates 9 of the series, it will be observed that the 10 seats 21 of said plates are irregular relative to the outer edges of said plates—that is, as the length of the plates increases the seats 21 of said plates are placed approximately in the center of said plates and at an angle relative 15 to the edges or ends of said plates. The seats 21 of the plates 9 are adapted to support the outwardly-bent ends 3 3 of the guard-rail 2, and in connection with these seats it will be observed that the ridges 22 22, carried by the 20 inner ends of said plates, are also disposed at an angle, whereby the outer base-flange 23 of the guard-rail 2 can be firmly supported upon said plates, while the inner base-flange 4 will be secured in the seats 21 21 by spikes 25 passing through openings 24 24 adjacent to said seats. The extreme end plates 25 25 of the series are provided with additional openings 26, whereby the inner base-flange 6 of the main rail 1 can be secured to the plates 30 25 25 by spikes 27 27, this being necessary, owing to the fact that considerable space exists between the outer bent ends 3 3 of the guard-rail and the main rail 1.

By referring to Fig. 2 of the drawings it 35 will be observed that when the series of plates are assembled the seats 17 and 21 of the series of plates are disposed upon a curved line relative to the alining outer edges of the series of plates, this also being true in connection with the ridges 15 and 22, carried by the 40 inner edges of the plates. The construction of my improved series of plates permits of the guard-rail 2 being easily and quickly spiked in position relative to the main rail 1, it being an extremely simple operation to arrange the plates in their order, as shown in Fig. 2. From the foregoing description, taken in connection with the drawings, it will be apparent that I have devised a novel form 45 of rail-plate to meet the existing conditions and requirements of rails now used, especially my improved guard-rail.

I do not care to confine myself to the exact 50 number of plates illustrated in the series or to their detail construction, and such other changes as are permissible by the appended claims may be resorted to without departing from the spirit and scope of the invention.

What I claim, and desire to secure by Letters Patent, is—

1. The combination with a main rail, and a guard-rail having a portion of its base-flange overlapped by the base-flange of said main rail, of a series of plates, said plates 65 having seats formed therein, to receive a por-

tion of the base-flange of said guard-rail, ridges carried by the ends of said plates and adapted to engage the outer base-flanges of said rails, and means to secure said rails upon said plates, substantially as described. 70

2. A main-rail and a guard-rail supporting means, comprising a series of rail-plates on which both the main rail and the guard-rail rest, the plates adjacent one end of the series being of greater length than the intermediate 75 plates of the series whereby to accommodate the outwardly-curved end of the guard-rail.

3. A main-rail and a guard-rail supporting means, comprising a series of rail-plates on which both the main rail and the guard-rail 80 rest, each plate having a seat to receive the guard-rail, the seats varying in position on the plates to conform to the outwardly-curved ends of the guard-rail.

4. A rail-plate provided on its upper face 85 with a seat lying below the upper face of said rail-plate, in combination with a guard-rail having its base-flange on one side resting in said seat, said base-flange of the guard-rail and the plate provided with registering openings, a main rail overlapping the base-flange 90 of the guard-rail, and a spike passed through said registering openings to secure both rails to the rail-plate.

5. A rail-plate for supporting a main rail 95 and a guard-rail, and comprising a plate having a ridge or flange on its upper face adjacent one end to engage with the outer edge of the base-flange of a main rail, and having a ridge or flange at its opposite end to engage 100 with the outer edge of the base of a guard-rail, the said plate having that part of its upper face on which the main-rail base and a part of the guard-rail base rests, on the same plane, and the remainder of its upper face, on 105 which the remainder of the guard-rail base rests, on a different plane, and a common securing means for the base on one side of the main rail and the base on the adjacent side of the guard-rail. 110

6. A main-rail and a guard-rail supporting means, comprising a series of rail-plates on which both the main rail and the guard-rail rest, some of said plates being of the same length, and other of said plates being of different lengths. 115

7. A series of rail-plates having seats formed therein, some of said plates being of a greater length than the other of said plates, ridges carried by said plates, and means to secure plates to said ties, substantially as described. 120

8. A series of rail-plates having seats formed therein, some of said plates being of a greater length than the other of said plates, 125 substantially as described.

9. A series of rail-plates adapted to support a main rail and a guard-rail having overlapping bases, the plates adjacent each end of the series being of greater length than the 130

intermediate plates whereby to accommodate outwardly-curved ends of the guard-rail.

10. A rail-plate for supporting a main rail and a guard-rail, and comprising a plate having a ridge or flange on its upper face adjacent one end to engage with the outer edge of the base-flange of a main rail, and having a ridge or flange at its opposite end to engage with the outer edge of the base of a guard-rail, the said plate having that part of its upper face on which the base of one of said rails and a part of the base of the other of said rails

rests, on the same plane, and the remainder of its upper face on which the remainder of the base of the other of said rails rests, on a different plane, and a common securing means for the base on one side of the main rail and the base on the adjacent side of the guard-rail.

In testimony whereof I affix my signature in the presence of two witnesses.

SIMON CLARY.
